UNITED STATES PATENT OFFICE.

GEORGE ROTTMAN, OF NEW YORK, N. Y., ASSIGNOR TO ROSETH CORPORATION, OF BROOKLYN, NEW YORK, A CORPORATION OF NEW YORK.

DUSTPROOF AND MOTHPROOF BAG.

Application filed October 9, 1920, Serial No. 415,925. Renewed May 7, 1923.

To all whom it may concern:

Be it known that I, GEORGE ROTTMAN, a citizen of the United States, residing at 252 Broome St., city of New York, in the county of New York and State of New York, have invented certain new and useful Improvements in a Dustproof and Mothproof Bag, of which the following is a specification.

My invention relates to a new and improved construction of dustproof and mothproof bag.

Bags of this character have been well known for a number of years and are extensively used for holding clothes during the summer time for preventing them from being injured by dust and moths.

For convenience in storage and shipping, these bags have been so constructed that they could be collapsed into the flat condition. As a result thereof, when these flattened bags are opened out into their extended position and the clothes were put into the bags, and the bags were then hung upon a hook in the usual manner, they tended to collapse into their flat condition so that the clothing became wrinkled and had to be repressed at the end of the summer.

The object of my invention is to produce a bag which can be readily collapsed and which has a definite box-like structure or shape when it is used.

Other objects of my invention will be disclosed in the following description and drawings which illustrate a preferred embodiment thereof.

Fig. 1 is a perspective view of my bag in the operative or extended position, and before the top thereof is closed.

Fig. 2 is a top view of Fig. 1.

Fig. 3 is a detail view showing the bag partially collapsed.

Fig. 4 illustrates how the bag is closed so as to prevent the entrance of dust and moths.

Fig. 5 is a side view partially in section showing how the bag is closed.

The bag is made of paper or the like and is creased along the lines 2, 10, 11, 12, 14, 15, 16.

Each side of the bag has pasted or otherwise secured thereto an inner flap 5, which is preferably centrally creased so as to correspond to the central crease 2 of each side.

This flap 5 can be held in the position

shown in Fig. 3 so as to permit collapsing 65 of the bag or it can be moved up into a position parallel to the bottom of the bag as illustrated in Fig. 2.

When the clothing has been hung upon the inner end of the hook 6 which extends into 60 the interior of the bag according to the well known construction and which is secured to the bag in any suitable manner, the bag is closed as follows:

The flaps 5 which are hingedly connected 65 to the side of the bag above the hook 6, are moved into their operative position, parallel to the bottom of the bag. These flaps can be made of the same kind of paper as the top of the bag or of stiffer material if this 70 is desirable.

The bag is now folded along the upper diagonal creases 14 until the front and back of the bag meet at the top. The top of the bag is now folded along the three top 75 creases 10, 11, 12, this folding being in alternate directions, so that the three top sections of the bag now form three closely adjacent layers.

The hook-like fastening means 3 which 80 are slidably mounted upon studs 4 secured to the rear of the bag are now slid inwardly or toward each other so as to firmly hold these three layers together.

The bag can now be hung up by means 85 of hook 6.

Experience has shown that if the flaps 5 are omitted in a bag having a construction otherwise identical with that herein illustrated, that when the bag is suspended from 90 its hook that the sides thereof bend internally so that the bag becomes collapsed and the clothing becomes badly wrinkled.

The flaps 5 constitute a very cheap, simple and efficient means for preventing 95 this.

I have described a preferred embodiment of my invention, but it is clear that numerous changes and omissions could be made without departing from its spirit. 100

I claim:

1. A dust-proof bag comprising a body portion and a top closure portion which extends above said body portion when the bag is open, said portions being so creased that 105 the entire bag can be folded flat, means for keeping the top closure portion in a closed and folded position, and flaps secured to the

sides of the said bag in a hinge-like manner below the mouth of said bag, the said flaps being creased so that they can be folded when the bag is collapsed into the flat condition, the said flaps being capable of being extended into positions substantially perpendicular to the sides of the said bag so as to maintain the said body in the extended position.

10 2. A dust-proof bag having a body portion and a top closure portion, the sides of the said bag being provided with central crease lines, and also with diagonal crease lines at the bottom and at the top of the said body portion, the said closure portion being provided with three continuous and parallel crease lines which extend around the four sides thereof and are substantially at right angles to the central crease lines of the said sides, means for maintaining the said closure portion in a closed and folded condition and flaps secured to the said sides in a hinge-like manner below the mouth of said bag, whereby the said flaps can be bent downwardly so as to be parallel to the said sides or can be bent upwardly so as to be

perpendicular to the said sides to keep the said body portion in extended position.

3. A dust-proof bag having a body portion and a top closure portion, the sides of the said bag being provided with central crease lines, and also with diagonal crease lines at the bottom and at the top of the said body portion, the said closure portion being provided with three continuous and parallel crease lines which extend around the four sides thereof and are substantially at right angles to the central crease lines of the said sides, means for maintaining the said closure portion in a closed and folded condition and flaps secured to the said sides in a hinge-like manner below the mouth of said bag, whereby the said flaps can be bent downwardly so as to be parallel to the said sides to keep said body portion in extended position, the said means consisting of clips, slidably secured to the rear of the said closure portion at the top thereof.

In testimony whereof I hereunto affix my signature.

GEORGE ROTTMAN.
